United States Patent Office.

RICHARD EATON, OF MONTREAL, CANADA EAST.

Letters Patent No. 60,865, dated January 1, 1867.

IMPROVED RAILROAD FREIGHT CAR.

The Schedule referred to in these Letters Patent and making part of the same.

TO ALL WHOM IT MAY CONCERN:

Be it known that I, RICHARD EATON, of Montreal, Canada, have invented a new and improved Freight Railroad Car; and I do hereby declare that the following is a full, clear, and exact description thereof, which will enable others skilled in the art to make and use the same, reference being had to the accompanying drawings, forming part of this specification, in which—

Figure 1 is a side elevation of a freight car, partly in section, taken in the line *x x*, fig. 2.

Figure 2 is an inverted plan, with interior parts exposed.

Figure 3 is an enlarged vertical section of a detached part.

Figure 4 is a horizontal section, in part, of a car.

Figure 5 is an enlarged plan of the crown plate detached.

Similar letters of reference indicate like parts.

This improvement relates to the construction of railroad freight cars, and is designed for increasing largely the capacity of a car for carrying freight. This object is accomplished by applying to a car two six-wheeled trucks with cogged friction-rollers, on which the body of the car rests, so constructed and arranged that the weight of the car and its load is equally divided and distributed upon the wheels and axles; thus allowing a heavier load to be put on the car without increasing the strain on any one of them. In constructing the car I reduce the "dead weight" very materially by substituting wrought for cast iron whenever it is possible, and particularly with the crown and centre plates, the buffer-boxes or draw-heads, and the axle-box guards or housings. Also, by making the roof of the car of sheet iron or steel, and setting strong and lightly-constructed uprights at the sides and ends of the car at proper distances from each other, to receive an upright flour barrel between them. By the diminution of "dead weight" thus effected in the construction of the freight car and the use of six-wheeled trucks arranged as hereinafter described, I am enabled to double nearly or quite the freight-carrying capacity of a car, or, in other words, carry two tons of freight to one of "dead weight," instead of one to one, according to the general rule with freight cars of ordinary construction. The practical advantage of this improved mode of constructing freight cars is that a train will be able to carry from thirty per cent. to fifty per cent. more paying freight, with the same hauling power of a locomotive, and thus largely increase the business and revenue of a railroad with the same amount of rolling stock.

A represents the supporting frame of the body of the car built in the ordinary way; B B are uprights on the sides and ends, to which the sheathing C C is fastened, which may be made of wood or sheet iron. The roof D D I make of sheet iron, either flat or corrugated, with ventilators in the top of the car when flat, or, when corrugated, formed by the corrugations of the overhanging sides or eaves, to prevent overheating of the perishable freight in warm weather. The openings for ventilation should be protected by wire gauze placed over them. E is the crown plate, and E' the centre plate, made of wrought iron, the former shown on an enlarged scale in fig. 5, made as light as possible by cutting out holes, *a a a a*, to rid it of surplus metal. The buffer-boxes or draw-heads F F are also made of wrought iron instead of cast iron, commonly used for the purpose, and open at the sides for the double purpose of admitting springs and lessening the weight of surplus metal. They are attached to the frame longitudinally by flanges on their sides and to the head-stock by angle-iron brackets. G G are the six-wheeled trucks, with their wheels, I I I, protected by sheet-iron housings or guards, H H, which are stiffened by flat or angle-iron knees or brackets, b b b, fig. 1, with their lower ends fastened to supporting bars, c c c, placed directly under the axle-boxes d d d. The outside truck frames, G G, are connected by cross-beams or bolsters, K K, which are also connected in the middle by the saddle L, on the upper side of which is fastened the lower centre plate E', the whole being sustained and kept in position by the central double-headed bolt e, as shown by fig. 3. Between the upper edge of the sides of the trucks and the bottom of the car over the middle wheel, are placed friction-cogged rollers, f f, figs. 1 and 2, which play loosely between iron or steel bearing-plates above and below, and allow a trifling oscillating or vibratory movement of the trucks, while they are held in place by the cogs or projections formed by little bars or studs on both sides of the rollers, which set into recesses in the containing friction or bearing plates above and below the rollers. The cogs prevent the rollers from slipping or from being moved or jammed out of place. The weight of the body of the car rests upon the friction-rollers, and they have sufficient side play to permit of the easy movement and adaptation of the trucks to any curves of the railroad track. The trucks are prevented from sluing around too far by the

overlapping of the cross-beams or bolsters K K upon the outsides of the transoms or bolsters M M, placed on the under side of the car, to which the crown plate E is fastened, (figs. 1 and 2,) while, however, sufficient space is left between the bolsters to suit the curves of the road. Around the interior of the car, securely fastened to the uprights B B, are placed two or more light horizontal iron bands or hoop-iron straps, g g, at such distances above the floor of the car as to reach the middle of the flour or other barrels, h h, arranged on end in tiers, as shown in figs. 1 and 4. Between the tiers of barrels thus loaded in a car I find great advantage in placing a light and strong board or frame, to keep the load steady in place and protect the chines of the barrels.

Having described my improvement and its advantages, what I claim as new, and desire to secure by Letters Patent, is—

1. I claim the truck for freight cars with six wheels and wrought-iron housings, H, constructed and arranged substantially as and for the purpose described.
2. I claim the cogged friction-rollers f f, placed between bearing plates on the car bed and truck frame, respectively, and operating substantially as described.

RICHARD EATON.
